SURFBOARD

George B. D. Parker, Raleigh, N. C.

Application January 29, 1948, Serial No. 5,129

5. Claims. (Cl. 9—11)

1.

This invention relates to surf boards of the sealed hollow hull type wherein the hull is formed of relatively thin aluminum sheets built about a corrugated skeleton, and in particular a comparatively thick boat-like corrugated frame having a rubber covered corrugated deck sheet, a sheet forming a bottom, and sheets forming sides with the edges of the sheets sealed by bonded rubber beads.

The purpose of this invention is to provide a surf board that is buoyant and at the same time reinforced sufficiently to prevent buckling when a force is applied at any point thereon.

The usual surf board is comparatively thin and of light weight construction and when double walls are used the thin material thereof has a tendency to buckle when the load is concentrated at one point. With this thought in mind this invention contemplates a continuous inner reinforcing for surf boards of the hollow type with the said reinforcing member corrugated longitudinally and transversely wherein the walls are supported at a plurality of points so that they are adapted to resist compression forces from the deck.

The object of this invention is to provide means for reinforcing a surf board internally without sacrificing the buoyancy thereof.

Another object of the invention is to provide means for reinforcing a surf board by incorporating elements within the hull of the board which prevents twisting, bending, or buckling at substantially all points.

A further object of the invention is to provide a surf board that is reinforced continuously throughout its length and width, which is of a simple and economical construction.

With these and other objects and advantages in view the invention consists of the new and novel combination, construction, and arrangement of parts as hereinafter more fully described, set forth in the claims appended hereto, and disclosed in the accompanying drawings, forming part hereof, wherein:

Figure 1 is a plan view of the surf board with part of the deck and covering thereof broken away showing the corrugated inner frame.

Figure 2 is a view showing a side elevation of the surf board.

Figure 3 is a view showing a longitudinal section through the surf board.

Figure 4 is a detail showing the inner corrugated frame riveted to a section of the hull of the surf board.

2.

Figure 5 is a typical cross section through the surf board.

Figure 6 is a view showing a front elevation of the surf board.

Figure 7 is a detail showing a method of welding the edges of the sheets forming the hull of the surf board.

Figure 8 is an exploded view showing the deck, bottom, and a side of the surf board separated.

Figure 9 is a front elevation of the surf board similar to that shown in Figure 6 with the outer part of the rubber bonding strip cut away to illustrate the sealing method of the edges of the materials.

Figure 10 is a view illustrating a modification wherein the corrugations in the deck are transversely positioned and those in the inner frame are positioned longitudinally.

Figure 11 is a cross section through the surf board shown in Figure 10.

Referring now to the drawings wherein like reference characters indicate corresponding parts the surf board of this invention is formed with a deck 10, a bottom 11, sides 12 and 13, a skeleton or inner frame 14, and a rubber mat 15 providing a deck covering.

The deck 10, as shown in Figures 1 and 5 is formed with longitudinally positioned ribs or corrugations 16 which provide reinforcing, and, as shown in Figure 5, the ribs extend upward through slots 17 in the mat 15.

The bottom and sides are substantially flat with arcuate ends, and the edges are joined by rubber bonds or beads 18 which are formed with slots 19 and 20 that receive the edges of the sheets of material as shown in Figure 5.

The edges of the sides, bottom, and deck may also be welded as shown in Figure 7 in which a side 21 is welded to a bottom 22 with welding beads 23 and 24 formed thereon.

The inner frame 14 is formed with relatively large corrugations 25, as shown in Figure 3, which extend transversely across the surf board and the surfaces thereof are formed with longitudinally disposed corrugations 26, as shown in Figure 5.

The inner frame 14 is connected to the deck and bottom through the high or low points of the corrugations by rivets 27, as shown in Figure 4, however it will be understood that the parts may be connected or attached by any suitable means.

In the design illustrated in Figures 10 and 11 the surf board is similar except that the deck is provided with transverse corrugations 28, and the

inner frame 29 is formed with relatively large longitudinaly positioned corrugations 30 and smaller transverse corrugations 31. In this design the deck 32, bottom 33, and sides 34 and 35 are similar in shape to corresponding elements of the design shown in Figure 1, and the edges of the parts are joined in a similar manner. The inner frame may also be connected to the parts by rivets or welding as desired.

With the parts arranged in this manner, and particularly with the parts made of aluminum, a buoyant, stable, and fast surf board will be provided, and all external forces or internal stresses will be absorbed by the inner frame.

It will be understood that other modifications may be made in the design and arrangement of the parts without departing from the spirit of the invention.

What is claimed is:

1. A surf board comprising a substantially hollow hull formed of bottom, side, and deck plates with the deck spaced from the bottom, and an inner corrugated reinforcing frame extending continuously from end to end of the hull retaining the plates in spaced relation continuously throughout the length thereof. 25

2. A surf board comprising a substantially hollow hull having bottom, side, and deck plates with the deck spaced from the bottom, and an inner corrugated reinforcing frame extending continuously from end to end of the hull with the high and low points of the corrugations in engagement with the deck and bottom respectively. 30

3. A surf board comprising a substantially hollow hull having bottom, side and deck plates with the deck plate spaced from the bottom plate, an inner reinforcing frame corrugated longitudinally and transversely positioned in the hull retaining the deck and bottom plates in spaced relation, and means connecting the high and low 35

points of the corrugations to the deck and bottom plates respectively.

4. A surf board comprising a substantially hollow full formed of bottom, side, and deck plates of lightweight metal, the adjoining edges of the plates being sealed in air and watertight relation, and stiffening means for the hull comprising an inner corrugated reinforcing frame extending continuously from end to end of the hull 10 retaining the plates in spaced relation and contacting the plates at spaced points continuously throughout the length thereof

5. A surf board comprising a substantially hollow hull having arcuate sides with converging ends formed of bottom, side and deck sheets of lightweight material, the adjoining edges of the sheets being joined in air and watertight relation, a rubber mat covering the deck, said deck having corrugations therein, and stiffening means 15 for the hull including a corrugated sheet extending continuously throughout the hull and supporting the deck and bottom sheets at spaced points continuously throughout the length thereof.
